DESIGN FOR A WRIST WATCH

Albert V. Stegeman, Jr., Fort Thomas, Ky., assignor to The Wadsworth Watch Case Company, Dayton, Ohio, a corporation of Kentucky

Application May 23, 1938, Serial No. 77,344

Term of patent 7 years

To all whom it may concern:

Be it known that I, Albert V. Stegeman, Jr., a citizen of the United States and a resident of Fort Thomas, in the county of Campbell and State of Kentucky, have invented a new, original, and ornamental Design for a Wrist Watch, of which the following is a specification, reference being had to the accompanying drawing, forming part thereof.

In the drawing:—

I claim:—

The ornamental design for a wrist watch, substantially as shown.

ALBERT V. STEGEMAN, JR.
